UNITED STATES PATENT OFFICE.

ANNIE ELIZA BRAY, OF LOS GATOS, CALIFORNIA.

JAR-CLOSURE.

SPECIFICATION forming part of Letters Patent No. 729,726, dated June 2, 1903.

Application filed October 29, 1901. Serial No. 80,464. (No model.)

To all whom it may concern:

Be it known that I, ANNIE ELIZA BRAY, a citizen of the United States, residing at Los Gatos, in the county of Santa Clara and State 5 of California, have invented a new and useful Jar-Closure, of which the following is a specification.

This invention relates to a closure for a jar specially adapted to contain preserved fruit; 10 and the object of the same is to prevent the fruit from fermenting and to facilitate the application and removal of the closure and also insure a tight fitting of the latter.

With these and other objects in view the 15 invention consists in the construction and arrangement of the several parts, which will be hereinafter more fully described and claimed.

In the drawings, Figure 1 is a perspective view of a jar embodying the features of the 20 invention and showing the manner of arranging the parts of the closure when pursuing the sealing operation. Fig. 2 is an enlarged transverse vertical section of the upper portion of the jar, showing the closure completely 25 applied.

Similar numerals of reference are employed to indicate corresponding parts in both views.

The numeral 1 designates the jar-body, which is of low or squatly form—that is, the 30 height and diameter are approximately equal—and at the upper portion thereof are exterior projections 2 for use in assisting to tightly apply or remove the closure, which will be hereinafter set forth. The upper extremity 35 of the body 1 is provided with an inwardly-extending offset 3, from the inner terminal of which a neck 4 vertically rises, and is provided with a series of spiral corrugations 5, which form threads. The neck 4 has an enlarged 40 diameter, so that the entrance and exit of the jar is materially increased in size for convenience in inserting or disposing the fruit or other material therein and likewise facilitating the removal of the contents of the jar. 45 The capacity of the jar will be the same as the ordinary devices of this class, and to prevent injury to the contents of the jar by the actinic light-rays it is proposed to color the jar in such manner as to obstruct the passage 50 of said rays into the interior thereof.

The mouth of the neck 4 is closed by a cover comprising a flat plate or disk 6, which

is substantially of the same diameter as the neck and rests upon the upper edge of the latter. The disk 6 is provided with a pendent 55 annular flange 7, which is located inwardly from the marginal edge of said disk and is designed to fit into the interior portion of the neck 4, a space being provided between the outer vertical wall of the flange and the inner adjacent surface of the neck. A pendent metallic flange or ring 8 is used with the plate or disk 6 and is provided with internal screw-threads to engage the spiral corrugations 5 to tightly bind the plate or disk 6 upon the upper edge of the neck, and thereby form a tight 60 closure for the mouth of the jar. The upper extremity of the ring 8 is formed with an inwardly-bent horizontally-disposed annular projection 9, which bears upon the upper side 70 of the plate or disk 6 a distance equal to, considered inwardly from the marginal edge of said plate or disk, the distance from the marginal edge of said plate or disk and the outer wall of the pendent flange 7. Interposed between the under side of the plate or disk and the upper edge of the jar-neck is a rubber or similar packing-ring or gasket 10, which is equal in width to the distance between the marginal edge of the plate or disk 6 and the outer 80 wall of the flange 7, so that when the plate or disk 6 is tightly pressed against the upper edge of the neck, with the ring or gasket 10 in place, said ring or gasket will be drawn down flat and project inwardly beyond the inner 85 surface of the upper portion of the neck and be confined between the ring 8 and the flange 7 to produce an absolutely tight or hermetically-sealed joint. By extending the annular projection 9 of the ring 8 inwardly over the 90 upper side of the edge portion of the plate or disk the pressure on the latter is extended over a greater surface, and the gasket or ring 10 will be more regularly flattened and maintained in such condition to avoid any possibility of entrance of air into the jar after the latter has been sealed. It will also be seen that the flange 7 insures an accurate disposition of the ring or gasket 10 when the plate or disk 6 is placed upon the upper edge of the neck, the said gasket or ring being first stretched around the flange 7 and held intact with the plate or disk when the latter is applied to the neck. It will also be observed 100

that the ring 8 is so proportioned that when it is applied it will extend over the full vertical distance of the neck, and this extended engagement, together with the upper annular projection 9 and the gasket or ring 10, interposed and held as set forth, will produce an air-tight closure. To assist in applying the ring 8, it has projections 11 at regular intervals thereon, which are intended to be engaged by a suitable gripping device, and these projections will be used conjointly with the projections 2 on the body 1 in the operation of closing the jar or removing the closure therefrom.

15 One means of closing the jar is shown by Fig. 1, and it will be seen that the plate or disk 6 is firmly held down on the upper edge of the neck 4 while the ring 8 is screwed onto the said neck, so as to bring the annular projection 9 at the top of the ring in binding contact with the said plate or disk. After the fruit, which is placed within the jar in heated condition, cools a vacuum is set up between the upper surface of the same and 25 the plate or disk 6, and the said plate or disk will by this means also be held firmly and reliably against the upper edge of the neck by the suction necessarily resulting. In opening the jar the ring 8 is first removed 30 and an implement of suitable character is inserted under the gasket or ring 10 to slightly raise the latter and the disk or plate to permit the air to enter and break the vacuum, after which the said plate or disk may be 35 readily removed.

The increased diameter of the jar will insure a more stable rest for the same and render it less liable to turn over. The large mouth provided by the neck of increased diameter will permit the insertion or disposal of fruit of large size within the body of the jar without mashing or breaking said fruit, and, furthermore, the said large mouth will easily admit a hand, and thereby allow the 45 perfect cleansing of the jar without the least inconvenience. A further advantage of the present improved form of jar is that no metal comes in contact with the contents of the jar, the plate or disk 6 being formed of glass simi-

larly to the body of the jar, and by making 50 the plate or disk of the material set forth it can be more readily cleansed, as can also the ring 8, if found necessary. It will also be observed that the gasket 10 will never become displaced in the sealing operation, because 55 the plate or disk 6 is held stationary after it is applied and the ring 8 alone is turned on the neck, and by this means the said gasket can with certainty be applied in such manner as to regularly and flatly engage the entire 60 upper edge portion of the neck.

Having thus described the invention, what is claimed as new is—

In a jar-closure, the combination with a jar-body having an upper neck provided with a 65 flat top edge, of a flat non-corrosive disk having a lower depending flange located at a distance inwardly from the marginal edge of said disk, a rubber gasket applied to the under edge portion of the disk and equal in 70 width to the distance between the outer wall of the flange and the margin of the said disk, and a ring independent of the disk to removably engage the jar-neck and having an upper inwardly-extending horizontally-disposed annular flange or projection to bear upon the upper side of the disk, the said flange or projection of the ring being also equal in 75 inward extent to the distance between the outer wall of the flange of the disk and the margin of the latter, whereby the flange of the disk will be located inwardly from and out of contact with the inner upper portion 80 of the neck and the gasket held flat upon the upper edge of said neck to produce a perfect 85 air-tight joint and also to hold the gasket in place against slipping, the disk being applied flat and held stationary on the upper edge of the neck while the ring is run downwardly over the neck in securing position.

In testimony that I claim the foregoing as my own I have hereto affixed my signature in the presence of two witnesses.

ANNIE ELIZA BRAY.
